UNITED STATES PATENT OFFICE.

WILLIAM H. CAPEHART, OF NEWELL, ALABAMA.

QUILTING-FRAME.

1,265,880.

Specification of Letters Patent. Patented May 14, 1918.

Application filed March 21, 1917. Serial No. 156,385.

To all whom it may concern:

Be it known that I, WILLIAM H. CAPEHART, a citizen of the United States, residing at Newell, in the county of Randolph and State of Alabama, have invented certain new and useful Improvements in Quilting-Frames; and I do hereby declare the following to be a full, clear, and exact description of the invention, such as will enable others skilled in the art to which it appertains to make and use the same.

This invention relates to improvements in quilting frames.

The object of this invention is the provision of a frame which may be adjusted to suit different conditions when quilting and one that can be readily taken down and packed away in a small place.

A still further object of this invention is the provision of a quilting frame of this character, which is provided with a plurality of rollers, which are so journaled in the frame as to be held against accidental rotation in one direction and provided with means whereby they may be rotated for tensioning the material placed thereon.

A still further object of this invention is the provision of a quilting frame, which is provided with a novel means whereby quilts of various sizes may be quilted by the adjustment of a single roller.

A still further object of this invention is the provision of a quilting frame provided with a pair of rollers constituting a top fabric carrying roller and a lining carrying roller, a receiving roller in the frame, receiving the end of the top and lining fabric, and novel means for the positioning of the lining carrying roller in a horizontal plane and at various distances from the frame.

A still further object of this invention is the provision of a quilting frame which is simple, practical and comparatively inexpensive in construction, and one that can be manufactured and sold at a comparatively low cost.

With these and other objects in view, the invention consists of the novel combination and arrangement of parts hereinafter more fully described and set forth in the claims hereto appended.

In the drawings:

Figure 1 is a view in side elevation of a

quilting frame made in accordance with my invention; the rear covering carrying roller being shown in raised position,

Fig. 2 is a top plan view of the same,

Fig. 3 is a longitudinal sectional view with the lining carrying roller positioned to prepare the frame for the making of large quilts,

Fig. 4 is a sectional view taken on the line 4—4 of Fig. 3,

Fig. 5 is a sectional view taken on the line 5—5 of Fig. 2,

Fig. 6 is a longitudinal sectional view illustrating the lining carrying roller positioned to prepare the frame for the making of small quilts.

Fig. 7 is a sectional view taken to illustrate the manner in which the rollers are held in position.

Fig. 8 is a sectional view taken on the line 8—8 of Fig. 2,

Fig. 9 is a sectional view taken on the line 9—9 of Fig. 2,

Fig. 10 is a sectional view taken on the line 10—10 of Fig. 2.

Like numerals of reference designate like parts and corresponding parts in all the figures of the drawings.

Referring more particularly to the drawings, the numeral 1 designates a plurality of vertical standards constituting supporting legs for supporting my improved quilting frame. The legs are arranged in spaced pairs, and each leg is provided adjacent its upper end with a transverse opening 2.

The pairs of legs are provided adjacent their upper ends in their opposing faces with inwardly extending upwardly inclined sockets 3 in which are secured the tapered ends 4 of the diagonally cross braces 5. The cross braces 5 are arranged in pairs and each pair is crossed at their medial portions as at 6 and extended in opposite directions and have their tapered ends 4 inserted in the sockets 3 in the legs 1, thus rigidly supporting the legs 1 in vertical position. The braces 5 are provided adjacent their upper ends on the inner side thereof with cut out portions 7, the purpose of which will be hereinafter fully described. A strengthening and reinforcing rod 8 extends from one pair of cross braces 5 to the other pair and has its ends connected to each pair at the point of crossing thereof as at 9.

A bearing housing 10 is removably secured upon the upper ends of each leg 1 by a pin 11, which pin is arranged transversely through the housings and openings 2 in the legs 1 to facilitate the removing of the housings 10 from the legs 1 when desired.

The bearing housings 10 are each provided with an inwardly extending recess 12 on the rear side and at the lower end thereof to receive the upper ends of the legs 1. The inner vertical walls 10' of the sockets 12 in the housings 10 have their lower edges arranged in the notches or cut out portions 7 of the cross braces 5, thus rigidly securing 15 the cross braces within the upwardly extending sockets in the legs 1 as shown in Fig. 5 of the drawings.

The bearing housings 10 at the rear of the frame have alined vertical grooves 13 20 in their front and rear faces for the purpose of receiving guide fingers 14 carried by the bearing housings 15, the purpose of which will be hereinafter fully described.

The rear bearing housings 10 are also provided adjacent their upper ends with horizontally alined openings 16, and one of the 25 housings is provided with a socket 17, which is arranged parallel to the openings 16, and which communicates at its inner end with a recess 17' formed in one wall of the openings.

The front bearing housings 10 are each provided with horizontally alined openings 16', which extend through their opposite 35 side faces and one of the front bearing housings also has an inwardly extending socket 18 arranged in its upper end, the bottom wall of the socket 18 extending below the wall of the openings 16', thereby establishing 40 communication between the opening 16' and socket 18, the socket opening out through the rear sides of the bearings as at 18'.

The front housings 10 each have an opening 20, extending transversely therethrough 45 and arranged at right angles to and in a plane below the openings 16'.

A lining receiving roller 21, which is located between the rear housing members 10, 50 is provided in its ends with inwardly extending screwthreaded bores 22, which aline with the openings 16. A stud 23 having a head 24, is formed with a cylindrical bearing sleeve 25 having a reduced inner screw-threaded end 26, which latter is adapted to extend through the openings 16 into the bores 22 of the lining roller, thus rotatably supporting the roller between the rear bearings 10.

60 The studs 23 on the right side of the quilting frame when looking from the front to the rear are provided on their bearings, sleeves 25, intermediate the ends thereof with ratchet wheels 27, which ratchet wheels 65 are adapted to be engaged by a pawl 28,

which is carried by a pin 29, which is arranged to extend through a diagonal slot 30, which extends through the outer side face of the bearing housings 10 at the right side of the machine when looking from the front 70 to the rear, and communicates with the socket 17 to permit the pin 29 and pawl 28 to be positioned therethrough.

A top fabric carrying roller 31 is arranged between the opposing faces of the 75 upper rear housings 15, which are arranged to rest upon the upper sides of the rear bearings 10 and it is secured therebetween by the studs 23 in the manner described of the securing of the roller 21 to the rear housings 10.

The rollers 21 and 31 are each secured between the opposing faces of the rear housings 10 and upper bearings 15 by the studs 23. Each of the studs 23 on the right side 85 of the machine are held against rotation by the pawls 28, which are secured to the pins 29, which are extended through the outer slots 30, which communicate with the sockets 17 in each of the rear bearings 10 and 15 90 on the right sides thereof, thus it can be seen that the rollers 21 and 31 are held against rotation in one direction.

A fabric receiving roller 32 is identical in construction with the rollers 21 and 31, and has inwardly extending screwthreaded bores 22 in its ends and it is located between the opposing side faces of the front bearing blocks 10 and rotatably secured therebetween by studs 23 in the manner similar to the 100 securing of the rollers 21 and 31 in position. To hold the receiving roller 32 against independent rotation, there is arranged in the opening 18' of the socket 19, a pin 23, which has secured centrally thereto, a pawl 34, 105 which has one end engaging the ratchet 27 carried by the stud 23, which extends into one end of the roller 32 in the manner previously described.

A pair of hollow rollers 35 are located 110 between each of the opposing faces of the front and rear bearings 10 and have one end secured to the bearings 10 by studs 36, which are identical in construction as the studs 23. The inner ends of the studs 36 115 are threaded into the hollow rollers 35, which are located between the opposing faces of the rear and front bearings 10. The opposite ends of the rollers 35 are reduced and arranged to extend transversely through its opening in the bearings 10 and has its end reduced and adapted to be keyed by engagement with the sleeve portion 24 of the stud 23, locking it in the bearings 10.

The rollers 35 that are journaled in the 125 front and rear housings 10 on the left side are locked therein against rotation by engagement with the studs 23, which hold the larger rollers in position. These rollers 35 are provided with cut out portions 37, which 130

engage the sleeve portion 25 of the studs when assembled. The lower roller on the right hand side of the machine has one end keyed in the rear bearings 10 and its opposite end held therein by the studs in the manner previously described.

The upper rollers 35 have one of their ends reduced to pass transversely through the bearings 15 and keyed therein by engagement with the top fabric carrying roller 31, their opposite ends are adapted to extend through and engage the inner sides 38 of the bearing block 39, which is secured to the outer side of the front bearings 10 by the pin 23, and the pin 23 or stud extends transversely through one end wall of the bearing block 39 into the end of the top roller 35, thus securing the same in position and against independent rotation.

The bearing blocks 39 and bearings 15 carrying the top fabric receiving roller is adapted to be lifted up as clearly shown in Fig. 1 in the initial operation, and a suitable batting or other material may be placed upon the lining which extends from the lining roller to the receiving roller, the top is then forced downwardly and the fingers 14 engaging the grooves 13 of the rear upper bearing members 10, holding the upper bearing 15 and its rollers against movement in a horizontal plane.

Each of the rear bearings 10 are provided with horizontally extending slots 40 which are arranged beneath the openings carrying the lining roller and at right angles thereto and extending transversely through the slots 40 are the extensions 41, which are held in various adjustment by pins 42, which extend through openings 43, which are arranged

at a spaced distance from each in the extensions 41, these openings permitting the lining roller or extensions to be adjusted at various positions away from the rear bearing members 10, to compensate for the quilting of various sizes of quilts.

Secured to the outer ends of the extensions 41 are bearing blocks 43', which are provided with a transversely alined opening 44 to receive the studs 23 therein for securing the lining roller 21 in the bearings 43', so that the same may be positioned at a spaced distance from the rear bearings 10 to permit the lining to be filled with batting or other suitable material before passing under the top fabric roller during the quilting operation.

Each head 24 of the studs 23 on the right hand side of the frame are provided in their outer faces with squared wrench receiving sockets 44' to permit the various rollers to be adjusted when desired.

When assembling the device, the device is set up in the manner described, the rear upper bearings 15 carrying the roller 31 is raised due to the connection of the bearing

blocks 39, with the front bearings, through the medium of the roller 35 and the studs 23. The top part of the fabric is wound upon the roller 31 carried in the bearings 15 and is extended downwardly therefrom over to and connected to the roller 32 in the front part of the frame. The lining roller 31 is removed from the bearing blocks 10 and placed in the bearing blocks 43' which are arranged on the extensions and the extensions are drawn rearwardly away from the rear bearings 10 and the lining is placed around the roller 32 and extends upwardly therefrom transversely across to the roller 32 to which it is connected and the operation of the device is obvious. The top fabric is designated A and is wound upon the upper rear roller and has its free edge secured to the front roller. The lining is wound upon the lower rear roller and designated B, and has its free end secured to the front roller so as to permit the lining and the fabric to be wound on the front roller by one operation.

What is claimed is:

1. A quilting frame comprising supporting legs, bearings removably secured to the upper ends of each of the legs, rollers removably secured to each of said bearings, a second set of bearings removably mounted upon certain of the first named bearings, a roller carried by said second named bearings and arranged parallel with the first named rollers, said second named bearings and roller adapted to be swung upwardly to permit placing thereon fabric material to be quilted, and means to hold the rollers against independent rotation, as and for the purpose specified.

2. A quilting frame comprising vertical standards, said standards arranged in pairs, cross braces connected to each pair of standards, bearing housings removably secured to the upper ends of each of the standards, a roller removably secured between the opposing side faces of each of the bearings, a second pair of bearing housings removably arranged on the upper ends of one pair of said first named housings, a roller removably secured to said second named bearings and parallel with the rollers in the first named bearings, a pair of rollers journaled in and removably secured in the first named bearings and arranged at right angles to the first named rollers, bearing blocks removably secured to the outer faces of one pair of bearing housings, a pair of rollers removably journaled in the second named bearings and bearing blocks and at right angles to the first named rollers and parallel with the first named right angularly related rollers, extensions removably mounted on certain of said bearings, bearing blocks carried by the outer ends of said extensions adapted to receive one of the first named rollers therein, and

130

means for holding the rollers against rotation.

3. A quilting frame comprising standards, said standards arranged in spaced pairs, cross braces rigidly supporting the standards in the spaced pairs, reinforcing rods connected to each of the cross braces at the medial portions thereof, bearings removably secured to the upper ends of the standards, one pair of bearings constituting the rear of the frame, the opposite pairs constituting the front thereof, a second pair of bearing housings seated upon the upper ends of the rear bearing housings, large rollers removably journaled between the pairs of opposing side faces of the rear bearing housing, a large roller journaled between the opposing faces of the front bearings, bearing blocks arranged on the outer side faces of the front bearings and removably associated therewith, studs removably inserted through the bearing blocks and bearings and into the rollers journaling the same thereto, smaller rollers journaled in the bearing blocks, and upper bearings, a second set of smaller rollers keyed in and removably secured in the rear and front bearings and at right angles to the larger rollers, means extending through certain of said bearings and blocks holding the rollers against independent rotation, and extensions slidably mounted transversely through the lower rear bearings and horizontally adjustable with relation thereto, and bearing housings carried by the outer ends of said extensions and adapted to receive the roller journaled in the rear lower bearings, as and for the purpose specified.

4. A quilting frame comprising a plurality of standards arranged in spaced pairs, each pair rigidly connected together by cross braces, one leg of each pair constituting the front and one leg of each pair constituting the rear thereof, bearings removably mounted upon the upper ends of the rear legs,

bearing housings removably mounted upon the upper ends of the front legs, said rear bearings provided with transversely extending openings arranged at right angles to one another, said rear bearings provided with transversely aligned openings and arranged at right angles to one another, said rear bearings being divided to provide upper and lower bearing housings, bearing blocks removably supported to the outer side faces of the front bearing housings in alignment with the top bearing housings, rollers journaled in the opposing side faces of the upper and lower bearings at the rear end thereof, a roller journaled in the opposing side faces of the front bearing housings, means extending through the bearing housings and into the rollers journaling the same thereto, means arranged in the bearings and engaging said first named means for holding the rollers against independent rotation, and a plurality of smaller rollers journaled in the front and rear bearings and bearing blocks and within the upper bearings and bearing blocks and arranged at right angles to the larger rollers, extensions slidably mounted in the rear bearings, bearing blocks carried by the outer ends of the extensions adapted to receive one of said first named bearing rollers therein, as and for the purpose specified.

5. A quilting frame including a support, a pair of relative spaced rollers journaled on said support, a pair of bearings carried by the support, means adjustably mounted on the support and provided with a pair of bearings, and a third roller adapted to be journaled on either of said pair of bearings.

In testimony whereof I affix my signature in presence of two witnesses.

WILLIAM H. CAPEHART.
